FLAT KNITTING FRAME

Arthur Richter, Berbisdorf Post Einsiedel,
GermanyApplication September 25, 1935, Serial No. 42,129
In Germany April 21, 1934

1 Claim. (Cl. 66—96)

This invention relates to a clock attachment in flat knitting frames.

In the usual clock attachments the lace finger rods are adjusted by a stop member controlled by a pattern mechanism which, as a rule, comprises a plurality of pattern segments controlled by a pattern chain, or the stop member is directly adjusted by a pattern chain or wheel. In every instance, the pattern mechanism is fed or changed after the narrowing operation is completed and, since the control of the entire clock attachment depends upon the racking of the main shaft, before the latter is racked back again. The result is that the narrowing operation proper, which has to be carried out during the racking of the main shaft, must be shortened to the extent of the time required for feeding or changing the pattern mechanism, which necessarily involves a reduction of the working speed of the machine during narrowing.

It is one of the objects of the invention to eliminate this drawback by providing, after adjustment of the stop member by its pattern mechanism, for bringing the latter out of engagement with the stop member for a new adjustment, the stop member being held in its position by special means until the narrowing operation is completed. The pattern mechanism is disposed on a horizontally adjustable slide.

Another object of the invention is to construct the device described in the preceding paragraph so that the time-consuming expulsion of the stop member into the outer end position, hitherto required and effected by a special wedge for each new narrowing course, can be dispensed with, the expulsion in connection with the device incompletely described above being only necessary when the stop member has to be adjusted towards the side turned away from its pattern mechanism.

The locking of the stop member by separate means would otherwise be released at the very moment when the newly adjusted pattern mechanism while moving into operative position engages the nose of the stop member. This would involve difficulties, as the pattern mechanism reaches the stop member at different times, according to adjustment.

This object is attained by providing, besides the means for holding the stop member adjusted by the pattern mechanism in position during readjustment of the mechanism, additional means for preventing the return of the stop member. The stop member locked by the first means is released after a narrowing operation has been completed and the newly adjusted pattern mechanism

is moved back into operative position, the stop member secured only against return and to be driven out with respect to its momentary adjustment being pushed into its new position by the pattern mechanism horizontally moved for this purpose when the mechanism has reached the stop member.

Another object of the invention is to render the additional locking means preventing the return of the stop member movable, so that the stop member to be moved back with respect to its momentary adjustment can be slowly returned to the newly adjusted pattern mechanism moved into operative position by means of its usual tension spring.

In this manner the hitherto required expulsion of the stop member into its inoperative end position can be dispensed with.

It is known to fix the stop member of clock attachments in position independently of its adjusting pattern mechanism, but this is done only for the purpose of shifting the stop member after each narrowing operation within one and the same narrowing course to the extent required to release the newly adjusted lower step of the segment of the pattern mechanism. The adjustment of the segment and thus the feeding of the pattern chain thereof are, however, effected only after the narrowing operation has been completed. Furthermore, according to the known method, the stop member must simultaneously be driven out into its inoperative end position at each narrowing course, as racking of the stop member relative to the new adjustment of the segment can be carried out only if the stop member is always racked backwards. This is possible during repeated narrowing in one and the same course, but cannot be done when several narrowing courses are made.

By way of example, the invention is illustrated in the accompanying drawings.

Figure 1 shows a clock attachment provided with a special fixing means for the stop member, seen from the side, the stop member being adjusted by the pattern mechanism and the fixing means being in inoperative position.

Fig. 2 indicates how the pattern mechanism after adjustment of the stop member is brought out of engagement therewith, whereas the fixing means engages the stop member.

Fig. 3 shows a clock attachment which besides the special fixing means for the stop member possesses an additional locking means to prevent the return thereof, the locking means being shown to hold the stop member instead of the

fixing means to permit the newly adjusted pattern mechanism moving into operative position to push the stop member into its new position if it has to be racked to the side turned away 5 from the pattern mechanism; and

Fig. 4 shows how this special movable means for locking the stop member against return makes it possible for the usual tension spring of the stop member to guide the latter slowly to- 10 wards the re-adjusted pattern mechanism if the stop member has to be racked back, the regular fixing means for the stop member being disengaged therefrom.

Referring to the drawings, the pattern mech- 15 anism 2 serving for adjusting the stop member 1 cooperating with the rod or rods 5 carrying the lace fingers comprises pattern segments of which only one is shown for the sake of simplicity and a pattern chain for adjusting these movable seg- 20 ments. The segments and their pattern chain are arranged on a slide 3 which, according to the invention, is horizontally adjustable for the purpose of moving the segments and their pattern chain for re-adjustment out of range of 25 the nose 6 of the stop member 1 when the latter is adjusted. As shown particularly in Figs. 1 and 2, the stop member 1 is in the meantime, until completion of the narrowing operation is effected, held in adjusted position by a member 4 replac- 30 ing the pattern mechanism 2 and consisting, in the example shown, of a member 4 attached to a bar 7 that can be raised and lowered and engaging a corresponding locking member 8 on the stop member 1 when the bar 7 is lowered 35 (Fig. 2). The pitch of the toothed or serrated locking members 4, 8 is of course proportioned to the gauge of the machine.

Instead of being horizontally immovably secured to the bar 7 the member 4 is simultane- 40 ously used for initiating the throwing over motions of the lace finger rod 5. As the loops are thrown over either to the right or left, the ad- justed stop member 1 must therefore carry out an additional motion towards these sides to per- 45 mit the transfer of the loops. For this purpose, the member 4, which is held in central position when no loops are covered, is attached to its bar 7 so as to be adjustable in horizontal direction. For adjustment a stepped wedge 9 is provided 50 against which the member 4 is held by a spring, not shown, and the arrangement is such that during non-covering the middle step of the wedge 9 is opposite the member 4. This middle step is so long that it will be in engagement with 55 the member 4 even if the latter has been lowered from its upper inoperative position into operative position according to Fig. 2. The vertical shifting of the wedge 9 produces the transfer of the loops on the lace points, to the adjoining frame 60 needles. Obviously this takes place after the loops in question have been disengaged from their frame needles so that the operation ini- 65 tiated by the wedge 9 forms one of the last operative steps of the transfer of loops. For this rea- son, when the transfer takes place, the nose 6 of the stop member 1 no longer is in engagement with the corresponding segment of the pattern mechanism 2. The pattern mechanism 2, as soon as the member 4 becomes lowered into locking 70 engagement with the member 8 of the stop mem- ber 1, is carried backwards from the nose 6 for shifting for the next operation, as shown in Fig. 2. It is possible for the wedge 9 also to shift the stop member 1 to the left. Fig. 2 shows how the 75 pattern mechanism 2 for shifting for the next

narrowing operation, is carried back from the nose 6 of the stop member 1 which meanwhile has been held fast by the member 4 on the rod 7, in which position of the working parts, the transfer of the received loops can take place by 5 shifting of the wedge 9. According to whether covering is to be effected to the right or left, the stepped wedge 9 is moved up or down whereby a corresponding lateral motion is given to the mem- 10 ber 4 and transmitted by the latter to the stop member 1.

The slide 3 in operative position is governed by an eccentric or cam 16 by means of the levers 19 and 20 and the roller 18 as shown in Fig. 1.

I have now described the clock attachment 15 shown in Figs. 1 and 2, which, owing to the mo- bility of its pattern mechanism and the arrange- 20 ment of a special fixing means for the stop member 1, has been enabled to effect re-adjust- ment of the pattern mechanism during the cov- 25 ering operation.

It will now be described how this clock attach- 30 ment is supplemented according to Figs. 3 and 4 so as to dispense with the expulsion of the stop member 1 into its inoperative end position re- 35 quired prior to each covering. The stop member is for this purpose, besides the member 8, fitted with a second locking means 12, 14 to prevent its return. This second locking means 12, 14 40 comprises the pawl 12 and the ratchet 14 at- 45 tached to the stop member 1. The two lock- 50 ing means 4, 8 and 12, 14 operate in timed rela- 55 tion, so that the locking of the stop member 1 effected by means of the members 4, 8 is released when a covering operation is completed and the 60 newly adjusted pattern mechanism 2 is moved back into operative position. Only the locking means 12, 14 preventing return of the stop mem- 65 ber 1 remain operative with the result that the pattern mechanism 2 while moving into oper- 70 ative position strikes the nose 6 of the stop mem- 75 ber 1 and pushes the latter in front of it into the new position if the stop member has to be driven out relative to its momentary adjustment. Wherever the pawl 12 may then engage the 80 ratchet 14 of the stop member 1 to prevent re- 85 turn motion, the member 1 with its ratchet 14 90 will simply be drawn away underneath the pawl 12, it being absolutely immaterial whether the stop member 1 has to be driven out for a new 95 covering operation in one and the same course or for a new course with respect to its adjust- 100 ment.

If the stop member 1 has to be racked back 105 relative to its adjustment, it is drawn by its spring 11 towards the pattern mechanism 2 which is re- 110 adjusted and returned to operative position. As the tension spring 11 of the stop member 1 is not in any way handicapped during this opera- 115 tion, the stop member will at great speed make 120 quite a hard contact with the pattern mechanism 2, especially if the member 1 has to be racked back a long distance. This drawback is elimi- 125 nated by imparting mobility to the locking means 12, 14 which prevent return of the stop member 1. The bearing 13 of the pawl 12 is disposed on 130 a swinging lever 15 controlled for instance by a cam disc, the arrangement being such that the pawl 12 is slowly guided back if the stop member 1 is to be returned (Fig. 4). In this manner the 135 effect of the spring 11 is damped, and the stop member 1, during its return motion, will slowly 140 engage the newly adjusted pattern mechanism 2.

It will be clear from what has been said above 145 that during racking back of the stop member 1 150

the pattern mechanism 2 must be already in operative position when the member 1 reaches the pattern mechanism 2 (Fig. 4), whereas during forward racking of the stop member 1 the pattern mechanism 2 will pass into operative position only after it has pushed the stop member 1 into its new position. For this reason, the motion of the slide 3 relative to operative position must be effected at different times. In the construction shown the slide 3 is for this purpose provided with two cam discs 16, 17 which are staggered relative to one another and which alternately adjust the slide 3 by means of a roller lever 19 and a rod 20, the roller 18 of the lever 19 being displaceable on its shaft to bring the lever 19 under the control either of the cam disc 16 or 17. The essence of the present invention consists mainly in that the time available for carrying out the actual narrowing operation does not have to be used in part for the shifting of the pattern mechanism 2, as was heretofore the case in all known clock attachments. For this reason the essential feature of the present invention is that the whole pattern mechanism 2, after adjustment 25 of the stop member 1, is withdrawn from the latter whereby the pattern mechanism 2, during one narrowing operation, can be freshly adjusted for the next narrowing operation. In Figs. 1 and 2 there is shown a clock attachment designed for such operation. Figs. 3 and 4 show this mechanism with the addition of a second device 12, 14 for preventing running back. The purpose of this device is to avoid the forcing of the stop member 1 to the right which was always heretofore necessary when the shifted pattern mechanism 2 is again returned to its position of use. The arrangement comprising ratchet device 14 is such that the stop member 1 is simply moved to the right or to the left according to the new position 35 it is to take up. For example, if the stop member 1 is to be shifted to the right for the next narrowing step, then it is intended to use the pattern mechanism 2 in the same manner as if the latter after its shifting, had again been pushed back into position of use. The pattern mechanism 2 then simply pushes the stop member 1 in front of it into the new position. This of course assumes that the engagement between the parts 4, 8 is inoperative, as otherwise these 50 would resist this shifting of the stop member 1. If the member 4 has been raised out of engagement with the serrated locking member 8 for this purpose, some other means must be provided for rendering inoperative the usual spring which 55 tends to pull the stop member 1 to the left, and this purpose is taken care of by the second latch means 12, 14. The pawl 12 engages the ratchet 14 and prevents backward movement of the stop member 1 to the left. If the corresponding segment 60 of the pattern mechanism 2 in its travel into position of use, should encounter the nose 6 of the stop member 1, the pattern mechanism 2 can push the stop member in front of it into the new position because the stop member will not 65 be obstructed in this operation by the second latch means 12, 14 which only operates to prevent return movement. The pawl 12 in this case is simply lifted and the stop member 1 slides under said pawl. If the operation is such that 70 the stop member 1 is to be shifted to the left from its previous position of setting then it is merely necessary to disengage the locking member 4 from the locking member 8 when the freshly adjusted pattern mechanism 2 is brought back into position of use. The aforesaid usual spring which

pulls the stop member 1 to the left then guides said member back to the corresponding segment. This takes place impulsively, and it is also a purpose of the second latch means 12, 14 to prevent this impulse. The arrangement, with this in view, is such that the pawl 12 can be shifted to the left. A lever 15 is arranged on the pawl for this purpose, which lever is rocked to and fro by means of an eccentric in such a manner that the pawl 12 is shifted to the left or to the right. If the stop member 1 is to be shifted to the left from its previous position of setting, then the lever 15 is so operated that the pawl 12 is moved to the left. In this manner the usual spring can pull the stop member 1 to the left and the speed of movement is determined by the pawl 12 and lever 15. It is essential in the present mechanism that the pattern mechanism 2 after setting of the stop member 1, must be moved back therefrom, in order that the pattern mechanism can be shifted for the next operation. The arrangement of the clock attachment necessary for this purpose can be seen in Figs. 1 and 2. Figs. 3 and 4 show the same mechanism with such improvements that the pattern mechanism shifted for the next operation pushes the stop member 1 in front of it into the new position in its path into the position of use, when the stop member is to be shifted to the right with respect to its previous setting, and on the other hand, the pawl 12 allows the stop member 1 to move to the left when the latter is to be shifted to this side from its previous setting.

The eccentric for the lever 15 operates in such a manner that the pawl 12, in shifting the slide 3 into the position of use, that is to the right, is carried back to the left. If the stop member 1 is shifted to the left then the spring of the stop member 1 will have free action to the extent determined by the backward movement of the pawl 12. If, however, the stop member 1 is already shifted to the right, nothing takes place when the pawl 12 is shifted to the left, because the stop member 1 will then simply be drawn below the pawl 12.

Obviously two eccentrics 16, 17 are required for shifting the slide 3 when the clock attachment is provided with the second latch means 12, 14 for the purpose just described, the movement of the slide 3 into the position of use in this case to take place at two different times according to whether the stop member has to be shifted to the left or to the right relatively to its previous setting, for the next narrowing operation. If a shifting to the left is to be effected, the slide 3 with its new adjusted pattern mechanism 2 must already have been returned to position of use when the stop member 1 has moved to the left to its new position, in order that the stop member cannot move beyond its setting. If the case is such that the stop member 1 is to be shifted to the right, then this shifting takes place by the pattern mechanism 2 of the slide itself since it then pushes the stop member 1 in front of it into the new position. In this case therefore the slide 3 arrives in the position of use at the same time as the stop member 1 and for this reason the two eccentrics 16, 17 are necessary.

The teeth pitch of the parts 4, 8 must correspond to the needle pitch of the machine because the stop member 1 has to be shifted to the extent of the needle pitch of the machine. The toothed bar 4, however, disregarding its movement dictated by the wedge 9, is fixedly attached to the rod 7. When the toothed bar 4 is lowered into

the toothed bar 8 of the stop member 1, then in any position of the stop member 1 engagement of the parts 4, 8 must be possible.

I claim:—

5 A clock attachment for flat knitting frames having lace finger rods, comprising a pattern mechanism, wherein a stop member for the lace

finger rods is adjusted by the pattern mechanism, means for bringing the pattern mechanism after adjustment of the stop member out of engagement therewith for new adjustment, and a fixing means holding the stop member in position until the covering operation is completed.

ARTHUR RICHTER.
